UNITED STATES PATENT OFFICE.

WALTER S. HOLZBAUR, OF WHITE HORSE, HAMILTON TOWNSHIP, MERCER COUNTY,
NEW JERSEY, ASSIGNOR TO JOHN E. MATHEWS, OF TRENTON, NEW JERSEY.

BARBER'S CHAIR.

1,168,071.

Specification of Letters Patent.

Patented Jan. 11, 1916.

Application filed September 14, 1914. Serial No. 861,675.

To all whom it may concern:

Be it known that I, WALTER S. HOLZBAUR, a citizen of the United States, residing at White Horse, Hamilton township, in the county of Mercer and State of New Jersey, have invented certain new and useful Improvements in Barbers' Chairs, of which the following is a specification, reference being had to the accompanying drawings.

10 This invention relates to an adjustable chair of that character generally employed by barbers and dentists, and has for its primary object to provide improved means for locking the leg and foot rest and the back 15 of the chair in their adjusted positions with relation to the chair seat.

The invention has for a further object to provide an extremely simple and effective locking device arranged beneath the seat of 20 the chair to securely hold the chair parts in their adjusted positions, and an operative lever connected to said locking means to release the same.

25 The invention has for a more specific object the provision of a rack bar connected to the leg rest of the chair and slidably mounted beneath the chair seat, a single spring held lever mounted upon the rotatable frame of the chair and coöperating with 30 said rack bar to lock the same against sliding movement, and a manually operable lever mounted upon the seat base of the chair and connected to said spring held lever to actuate the same and release the rack bar.

35 The invention has for a further general object to materially simplify the construction and increase the durability of devices of the above character whereby the manufacturing cost of adjustable chairs is reduced to a minimum.

With the above and other objects in view as will become apparent as the description 40 proceeds, the invention consists in certain constructions, combinations and arrangements of the parts that I shall hereinafter fully describe and claim.

45 For a full understanding of the invention, reference is to be had to the following description and accompanying drawings, in which—

50 Figure 1 is a perspective view of an adjustable chair constructed in accordance with the present invention; Fig. 2 is a vertical section; Fig. 3 is a plan view, the chair

seat being removed. Fig. 4 is a section taken on the line 4—4 of Fig. 3; Fig. 5 is a detail perspective view of certain of the parts.

Referring in detail to the drawings, 5 designates the standard or pedestal of the 60 chair upon the lower end of which the base flange 6 is integrally formed. The upper end of this pedestal is also formed with an annular flange upon which the bearing plate 7 is secured. This bearing plate is formed 65 with a central upstanding cylindrical stud or boss 8.

9 indicates the inverted bearing cup or plate which is opposed to the bearing plate 7, and is formed with a central opening to 70 receive the cylindrical boss 8. This inverted bearing cup is retained in position by means of a cap plate 10, which is secured to the boss 8 by the screws indicated at 11. Between the opposed bearing plates 7 and 9 a series 75 of bearing balls 12 are arranged.

The seat frame 13 is secured in any suitable manner upon the rotatable bearing plate 9. This seat frame as clearly shown in Fig. 3 consists of an outer marginal wall 80 14 which is connected to the bearing plate 9 by diametrically opposed radial arms 15. In practice, these arms are preferably formed integral with the bearing plate.

Upon the inwardly projecting flange of 85 the marginal wall 14 of the seat frame, at the rear thereof, and upon opposite sides of the frame, the bracket plates 16 are secured. The chair back indicated at 17 is pivotally mounted between and upon these 90 bracket plates. To the forward edge of the marginal wall 14 of the seat frame and at each side thereof, upwardly projecting brackets 18 are secured upon which the side bars 19 of a combined leg rest and foot support are fulcrumed. These bars project above the brackets 18 and upon the same, the forward ends of the arm rests 20 are pivotally mounted, the rear ends of these 95 arm rests being pivotally connected as at 21 to opposite sides of the chair back 17 adjacent the brackets 16 upon which said chair back is mounted.

The side bars 19 of the leg rest are connected at a point slightly below the brackets 18 upon which said bars are mounted, by a horizontal rod 22. The diverging arms 23 of a Y shaped bar are loosely mounted at their extremities upon said rod adjacent its ends. These arms 23 extend inwardly from 110

the side bars 19 of the leg rest over the seat frame of the chair, the central arm 24 of said Y shaped bar being disposed in line with the axis of the chair pedestal upon which the chair body is rotatably mounted. To this central arm 24 of the bar, the forward end of a slidable bar 25 is secured. This latter bar is movable in a guide loop 26 which is fixed upon the seat or sleeve 26 which is fixed upon the seat frame 13, and has a series of rack teeth 27 formed in one of its longitudinal edges. Upon the upper surface of the bearing plate 9, a bell crank lever 28 is fulcrumed as at 29 upon one side and slightly to the rear of the chair pedestal 5. One arm of this lever has a lug 30 formed upon its extremity for engagement with the rack teeth 27 of the bar 25. To the other arm of said bell crank lever, one end of a coil spring 31 is connected, the other end of said spring being suitably secured to the seat frame 13. This spring normally acts to hold the lug 30 of the lever yieldingly in locking engagement with the rack teeth of the bar 25.

25 A horizontally disposed rod 32 is rotatably mounted in suitable bearings 33 formed upon the under side of the seat frame 13 and is equipped upon its outer end with a handle 34. Upon this rod, an arm 35 is secured, said arm being provided with a collar 36 upon one end in which a set screw 36 is threaded whereby the arm may be adjustably secured upon said rod. This arm it will be observed extends from the collar 35 upon one side of the rod 32 and is curved and reversely extended upwardly and rearwardly over one of the arms 15 of the seat frame 13. One end of a rod 37 is connected to this rearwardly projecting end of the curved arm 35. Said rod loosely extends through an opening in the arm of the lever 28 to which the spring 31 is connected, and a nut 38 is threaded upon said rod for engagement with the lever arm.

45 From the foregoing description taken in connection with the accompanying drawings, it is believed that the construction, manner of operation and several advantages of my improved adjustable chair may be clearly and fully understood. In order to adjust the chair back and leg and foot rest with respect to the seat, the operator grasps the handle 34 and pushes the same forwardly toward the front of the chair, there- 50 by rotating the rod 32. In this rotation of the rod, the upper end of the arm 35 is moved forwardly of the axis of said rod and through the medium of the rod 37 and nut 38 thereon, the bell crank lever 28 is oscil- 55 lated, upon its fulcrum, to disengage the lug 30 of said lever from the teeth 27 on the bar 25. The chair back may then be tilted to any desired inclined position, the leg and foot rest of course being extended forwardly and upwardly in such tilting move-

ment of the chair back. The Y shaped bar 23 being connected to the rod 22 extending between the side bars of the leg rest, it will of course be obvious that the bar 25 will be drawn forwardly through the guide loop 70 26. Upon the release of pressure on the handle 34, the spring 31 acts to immediately return the bell crank lever 28 and the arm 35 to their normal positions, so that the lug of the bell crank lever is again engaged with the teeth of the bar 25 and said bar securely locked against further sliding movement. Thus the adjustable parts of the chair are positively held in their adjusted positions.

It will be noted that the pull or strain 80 upon the bar 25 is in a horizontal plane, and the locking lever 28 is also mounted for movement in a horizontal position. Therefore, the pressure of the bar against the arm of said lever instead of urging the lever 85 arm outwardly to its released position, acts to create a greater frictional bearing pressure of the lug on the end of the arm against the rack teeth, thus obviating the accidental or unintentional release of the bar 25 by a 90 suddenly applied and excessive pressure upon the foot rest.

From the above it will be seen that I have devised a very simple and efficient locking device for adjustable barbers' or dentists' 95 chairs which is not liable to get out of order, is extremely strong and durable in practical use and may be embodied in a chair structure at comparatively small cost. Access may be readily had to the several elements employed 100 by simply removing the seat cushion indicated at 39, in order that accumulations of dust and dirt may be removed. The leg rest is of the usual form employed in such chairs, while the foot rest 40 is of the non-adjustable 105 type and is permanently secured upon the forwardly projecting base portion of the leg rest. It is to be understood, however, that while I have above described a particular 110 mounting of the seat frame and the adjustable parts of the chair, my improved locking device is also applicable to various other constructions of such chairs, and I do not therefore desire to be limited to such mounting of the parts of the chair body in putting 115 the invention into practical use. I also re-serve the privilege of resorting to all other legitimate modifications in the form, proportion and arrangement of the several 120 parts as may be fairly embodied within the spirit and scope of the appended claims.

Having thus described the invention, what is claimed is:

1. In a barber's chair, the combination 125 with a pedestal, of a seat frame rotatably mounted on said pedestal, a chair back pivotally mounted upon said seat frame, a leg rest pivotally mounted on the seat frame, an arm rest pivotally connected to said back and leg rest, a Y shaped frame having its 130

- outer end connected to the leg rest portion and its inner end formed with an extension, a guide on the seat frame, a horizontally disposed rack bar having one end guided and retained by said guide and its other end secured to the extension of the Y shaped frame, a bell crank lever pivoted to the seat frame in horizontal relation to the said rack bar, one arm of said lever constructed to engage the rack, a spring having one end connected to the seat frame and the other end secured to the other arm of said lever, a rod having one end adjustably connected to said arm near the connection of the spring, a segment shaped vertically disposed curved arm having its upper end connected to said rod and a right angled shaped hand lever pivoted to the seat frame, having its horizontal limb connected to the lower end of said curved arm and having its vertical limb formed with a handle arranged practically under one of the arm rests and protected from contact thereby and in easy reach of the hand of the operator.
2. In a barber's chair, the combination with a pedestal, a circular support mounted upon said pedestal provided with a centrally disposed vertical stud, a circular turn table mounted on said stud and capable of rotation thereon, a series of arms projecting laterally from said turn table, a lug formed on one of said arms and having a circular shaft bearing therein, a lug formed on one of the other arms and having an angular guiding opening therein, a rack bar guided horizontally in said opening, an arm connected to the other end of said rack bar, a leg section pivotally connected with said arm, arm and back rests connected in proper relation, a yoke shaped seat frame to which the back and arm rests are adjustably connected, said seat frame being secured to the arms of the turn table, a bell crank lever fulcrumed at its corner to the turn table and having one arm engaging said rack bar, a spring connected to the seat frame and to the other arm of said lever upon one side of said arm, an adjustable rod leading from the end of the last named arm of said lever, a curved vertically disposed arm secured to said adjustable connection, a rod mounted in the circular shaft bearing upon the arm of the turn table and having said circular arm mounted upon its inner end, and a vertical terminal formed on said rod and carrying a handle for operating said rod, said handle and rod being disposed at one side of the chair and practically under one of the arm rests of the chair.
- In testimony whereof I hereunto affix my signature in the presence of two witnesses.
- WALTER S. HOLZBAUR.
